UNITED STATES PATENT OFFICE

LLOYD W. PATCH, OF WASHINGTON, DISTRICT OF COLUMBIA, AND ARTHUR K. MCRAE, OF DENVER, COLORADO, ASSIGNEES TO AMERICAN BABY BONDS CORPORATION, OF DENVER, COLORADO, A CORPORATION OF COLORADO

DESIGN FOR A TRADE COUPON OR THE LIKE

Application filed May 29, 1930. Serial No. 35,856. Term of patent 14 years.

To all whom it may concern:

Be it known that we, LLOYD W. PATCH, a resident of Washington, in the District of Columbia, whose post-office address is 3610 Albermarle Street N. W., and ARTHUR K. MCRAE, a resident of Denver, in the county of Denver and State of Colorado, whose post-office address is 1242 S. Gilpin Street, Denver, Colorado, both citizens of the United States, have invented a new, original, and ornamental Design for a Trade Coupon or the like, of which the following is a specification, reference being had to the accompanying drawing forming part thereof.

The figure is a plan or face view of a trade coupon showing our new design.

We claim:

The ornamental design for a trade coupon or the like, as shown.

LLOYD W. PATCH.
ARTHUR K. MCRAE.
